UNITED STATES PATENT OFFICE.

WILLIAM J. HECK, OF NEWARK, NEW JERSEY.

STAMPING DEVICE.

Application filed October 25, 1927. Serial No. 228,598.

This invention relates to a hand stamping or marking device such as used for stamping clothes for identification when sent to the laundry, and has for its principal object to 5 provide a simple construction whereby the marking of the clothes can be conveniently and quickly accomplished.

With this and other objects in view my invention consists in the novel construction, 10 combination and arrangement of parts as will be hereinafter more fully described and defined in the appended claims.

In the accompanying drawing in which similar reference characters denote corresponding parts Fig. 1 is a vertical section, partly in elevation, of my improved hand stamp; Fig. 2 is a cross section on line 2—2 of Fig. 1 and Fig. 3 is a sectional view of a detail showing the suspension of the movable die.

20 Referring more in detail to the drawing, the stamping or marking device comprises a frame 10 of conventional shape having a base 11 and an arm 10² adapted to carry the movable die. The base 11 is formed at its front 25 end with an upwardly projecting member or block 12 which constitutes the stationary die. At the rear of said member 12 and adjacent thereto is provided a second upwardly projecting part 13 whose upper face 13' is slanting 30 downwardly toward its forward end and which at its sides and front end is provided with upwardly projecting and longitudinally extending ribs 13², 13³. The inner face of the end rib is made slanting so as to be perpendicular to the sloping surface 13'. This part 35 13 constitutes a bed or support for an inking pad 14 which is adapted to more or less snugly fit between the ribs 13² and bear with its forward end against the slanting face of the front rib 13³. Fixed to the base 11 as at 15' 40 is a clasp 15 for the attachment of the article to be marked. According to the present embodiment this clasp is in form of a resilient plate 15 adapted to normally bear flatly and 45 with pressure against the base and which is formed with recesses 15² and 15³ through which project the parts 13 and 12 respectively.

The rear edge of the recess 15² is formed with a resilient tongue 16 which is adapted to 50 project vertically above the bed and to bear normally with pressure against the rear edge of the inking pad 14 and thereby hold the latter in position on the bed. The front end of the clasp 15 is slightly extended beyond 55 the upper face of the base to form a grasp

15⁴. The recess 15³ is slightly larger in area than the stationary die 12 so that its edges when embracing the article deposited on the stationary die will stretch the portion to be stamped or marked and hold it taut during 60 the stamping operation.

The movable die 16 is adapted to be supported in the head piece 10' of the frame 10 to project vertically downward in alignment 65 with the stationary die 12. To this end said head piece 10' is provided with a vertical cylindrical bore 10³ which at its rear terminates in a groove 10⁴ and at its upper front end in a forwardly slanting groove or bore 10⁵. The die 16 is movably borne in a hollow cylindrical socket 17 which normally is 70 adapted to bear in the bore 10³ and which is formed at its upper end with diametrically opposed pintles or pivots 18. These pivots are adapted to be rotatably borne in plates 75 or the like 19 fixed to the head piece 10' as at 19'.

Owing to its pivotal support the socket 17 will be capable of being oscillated on a horizontal axis into the dotted line position 80 (Fig. 1) so that its lower portion will extend through the groove 10⁴ and its upper end through the groove 10⁵. To hold said socket normally in vertical position I provide a 85 presser finger 20 borne in a longitudinal bore 10⁶ of the arm of the frame and acted upon by a spring 21 mounted in the latter. The forward end of said finger is adapted to constantly press against said socket retaining it 90 in the bore 10⁵.

The die 16 comprises a plunger 16' capable of being reciprocated vertically in said socket 17 and formed at its upper end with a knob or grasp 16² and at its lower end with a stem 16³. This stem is adapted to project outwardly from the lower end of the socket and threadedly or otherwise engage a frame 22 carrying a rubber stamp 23 or the like. The plunger is held in the socket by the mouth-piece 22' formed on the frame 22 or by other suitable means and is impelled upwardly by a spring 16⁴ mounted in the socket.

The rear end of the arm of the frame may be made hollow as at 10^a to form a receptacle in which may be accommodated different rubber stamps, ink for the inking pad or other accessories. The open bottom of the receptacle 10^a may be provided with a hinged cover 24 having a suitable catch 25 for locking it 105 in closed position.

The operation of my stamping device is as follows:

On raising the front end of the clasp 15 the article *g*, such as handkerchief or the like, 5 to be stamped or marked is placed over the stationary die 12. On releasing said clasp 15 the edges of its front recess 15³ will embrace the goods around the die 12 and stretch the same taut. Thereupon the movable die 16 10 is grasped in one hand and swung rearwardly into the dotted line position, at the same time depressing the same in its socket, so that the stamp 23 will be brought into contact with the inking pad 14 and inked. On swinging said die 16 back into normal position it 15 is depressed in its socket 17 to be struck against the goods *g* deposited on and held taut on the stationary die. Both the inking and marking can thus be performed by one hand 20 in one operation, while the goods can be attached to and detached from the stationary die very conveniently with the other hand.

The bed 13 of the inking pad may be arranged at a sufficiently high elevation from 25 the base and at such angle of inclination that a depression of the plunger during the inking process will not be necessary.

Since various modifications may be made in the construction without departing from 30 the principle of my invention I do not wish to restrict myself to the details described and shown.

What I claim is:

1. A hand stamping device, comprising a 35 frame having a base, means on the base for the attachment of the article to be stamped, in taut condition, a die suspended from the frame above said base to be movable ver-

tically for the stamping operation and capable of being oscillated on a horizontal axis, 40 and means for supporting inking means in a slanting position on said base to be in the path of said die when oscillated.

2. A hand stamping device, comprising a frame having a base, means on the base for 45 the attachment of the article to be stamped, in taut condition, a die suspended from said frame above said base and comprising, a hollow member capable of oscillating on a horizontal axis, a plunger movably supported in 50 and projecting from said member and whose lower end carries the die proper, means normally holding said oscillatory member in vertical position, and means for supporting an inking means in an inclined position to 55 be in the path of the die proper when the latter is swung on its axis.

3. A hand stamping device comprising a frame having a base, a spring clasp on said 60 device for attaching the article to be stamped on said base in taut condition, a die suspended from said frame to normally extend perpendicularly to said base, said die comprising a hollow member pivotally supported in said frame to swing on horizontal axis, a 65 spring actuated plunger supported in said hollow member to move longitudinally therein and to project outwardly therefrom and carrying a die proper and means on said base adapted to engage and support an ink pad in a slanting position so as to be in the path of said die proper when the latter is 70 swung on its axis.

In testimony whereof I affix my signature.

WILLIAM J. HECK.
